UNITED STATES PATENT OFFICE

FRANK L. ROE, OF CHICAGO, ILLINOIS

DESIGN FOR A LADY'S PORTABLE SLIPPER CONTAINER

Application filed July 29, 1929. Serial No. 32,243. Term of patent 3½ years.

To all whom it may concern:

Be it known that I, FRANK L. ROE, a citizen of the United States, residing at Chicago, in the county of Cook and State of Illinois, have invented a new, original, and ornamental Design for a Lady's Portable Slipper Container, of which the following is a specification, reference being had to the accompanying drawing, forming a part hereof.

The figure is a perspective view of a lady's portable slipper container, in a closed position, showing my new design.

I claim:

The ornamental design for a lady's portable slipper container, substantially as shown and described.

FRANK L. ROE.
